UNITED STATES PATENT OFFICE.

WILLIAM A. SNYDER, OF MAZOMANIE, WISCONSIN.

RAZOR-GUARD.

1,346,855.

Specification of Letters Patent. Patented July 20, 1920.

Application filed October 31, 1919. Serial No. 334,811.

To all whom it may concern:

Be it known that I, WILLIAM A. SNYDER, a citizen of the United States, residing at Mazomanie, in the county of Dane and State 5 of Wisconsin, have invented certain new and useful Improvements in Razor-Guards, of which the following is a specification.

My invention relates to new and useful improvements in a razor guard and has for 10 its principal object the provision of a device adapted to be applied to the blade of an ordinary razor for converting the same into a safety razor.

Another object resides in the construction 15 of the guard in such a manner that it may be swung to either side of the blade.

Further objects reside in the provision of 20 novel means for securing the guard on to the blade and for holding the guard in its adjusted position on either side of the blade.

With these and other objects in view my 25 invention consists in the novel details of construction and arrangement of parts which will be more clearly understood from the following specification and drawings in which:—

Figure 1 is an elevation showing one side of the razor blade and guard.

Fig. 2 is an elevation showing the opposite side of the blade and guard.

Fig. 3 is an end view.

Fig. 4 is a transverse vertical section on the line 4—4 of Fig. 2, and

Fig. 5 is a horizontal section on the line 35 5—5 of Fig. 2.

In the drawing A indicates a razor blade of usual construction and B the guard adapted to be connected to the blade.

The guard B comprises a plate 1 having 40 the lower edge offset as indicated at 2 and said offset portion is provided with a plurality of longitudinally spaced depending tongues 3. As indicated more particularly in Fig. 4 of the drawings the depending 45 tongues 3 extend at a slight angle so that the lower ends thereof will be in substantially vertical line with the plate 1. A spring member is connected to the plate 1 and comprises an upper arm 4 and a lower 50 arm 5 extending parallel therewith and in spaced relation as more clearly illustrated in Figs. 2 and 4 of the drawings. The arm 4 is secured to the plate 1 by means of rivets 6 or other suitable fastening means. As 55 shown the arm 4 of the spring member ex-

tends parallel with the plate 1 whereas the arm 5 is spaced therefrom and extends adjacent the lower ends of the tongues 3. As illustrated in the drawings the razor blade A will be received between the lower arm 5 60 of the spring member and the depending tongues 3. The offset portion 2 will engage over the top edge of the blade as more clearly illustrated in Fig. 4 of the drawings. The plate 1 is provided on its upper edge 65 with the eyes or loops 7. A rod 8 extends through the sleeves or eyes 7 and by this construction the plate 1 is pivotally mounted upon the rod. The rod 8 has a right angle extension 9 on one end thereof and the end 70 of the right angle extension 9 is formed with the rod or extension 10 which extends parallel with the rod 8.

A plate 11 is provided on the upper edge 75 with the sleeves or eyes 12 and the extension 13 or rod 10 is adapted to pass through the eyes or sleeves whereby the plate 11 is pivotally connected on the rod. The lower end of the plate 11 is vertically slit from the lower edge thereof to form a plurality of 80 teeth 13. These teeth will be twisted at substantially right angles as more clearly set forth in Fig. 4 of the drawings and the lower edge of the teeth will be rounded for a purpose to be later described. 85

A plate 14 is received on the rods 8 and 10, adjacent the right angle extension 9, and this plate is provided with a threaded opening for a purpose to be later described. A plate 15 is also mounted upon the rods 8 and 90 10 and is provided with an opening for a purpose to be later described.

A washer 16 is received on each of the rods 8 and 10 and each washer is provided with a downwardly extending tongue 17 95 provided with a notch in the lower end thereof. The notch in the tongue of the washer carried on the rod 8 is adapted to engage the upper edge of the plate 1 and the notch in the tongue of the washer carried on the rod 10 is adapted to engage the upper edge of the plate 11. A spacing plate 18 is adapted to be received on the rods 8 and 10 between the plate 15 and washers 16. 100

A plate 19 is carried on the opposite ends 105 of the rods 8 and 10 and corresponds to the plate 14. A plate 20 is also carried upon the rods and correspond to the plate 15. Each of the plates 19 and 20 is provided with an opening for a purpose to be later described. 110

Washers 21 are received on each of the rods 8 and 10, between the plates 19 and 20, and each of these washers is provided with a downwardly extending tongue 22 provided 5 with a notch 23 in the lower end thereof. As shown more clearly in Fig. 4 of the drawings the notch in the washer carried on the rod 8 is adapted to engage over the upper edge of the plate 1 whereas the notch in 10 the washer carried by the rod 10 is adapted to engage over the upper edge of the plate 11. Spacing plates 24 are carried upon the rods 8 and 10 between the plate 19 and washers 21. Each of these spacing plates 24 are 15 provided with openings in alinement with the openings formed in the plates 19 and 20. A rod 25 is adapted to extend through the plates 14, 15, 18, 19, 20, and 24 and said rod is provided on one end with a right angle 20 extension 26, forming a handle, and the opposite end is screw-threaded as indicated at 27. The end 27 of course passes through the threaded openings in the plates 14, 15, and 18 and has engagement with the threads in 25 the opening in the plate 14.

From the above detailed description it is thought that the operation as well as the advantages of my guard will be clearly understood. When in use the parts will be assembled 30 in the manner shown and the razor blade A will be received between the downwardly extending tongues 3 and the arm 5 of the spring member. This spring member will securely hold the blade in position and the offset portion 2, engaging the upper edge 35 of the blade, will properly space the blade. The teeth 13 will be brought adjacent the blade as shown more particularly in Fig. 4 of the drawings and when the parts are 40 swung into this position the rod 25 will be rotated so that all of the plates will be drawn into frictional contact and securely hold the parts in position. If it is desired to swing the plate 11 with the teeth 13, to the opposite 45 side of the blade the rod 25 is rotated so as to loosen the frictional engagement of the plates 14, 15, 18, 19, 20, and 24, with the washers 16 and 21. When this had been done the plate 11 with the teeth 13 may be 50 swung as indicated by the dotted lines in Figs. 3 and 4 of the drawings and until the teeth 13 engage or lie approximate the opposite face of the blade. When in the proper position the rod 25 will be again adjusted to 55 hold the parts in position. It will be noted that the upper edges of the plates 1 and 11 being received in the notches of the washers 16 and 21 will allow said plates to swing with the washers and independently of the 60 plates 14, 15, 18, 19, 20 and 22.

I wish to lay particular stress on the fact that when inserting the blade A in position it may be moved longitudinally of the guard and the edge will not be dulled.

65 The foregoing description and the draw-

ings have reference to what may be considered the preferred, or approved form of my invention. It is to be understood that I may make such changes in construction and arrangement and combination of parts, materials, dimensions, etc., as may prove expedient and fall within the scope of the appended claims.

Having fully described my invention what I claim as new and desire to secure by Letters Patent is:—

1. A razor blade guard comprising a plate, means for connecting the plate to the blade, eyes formed on the upper edge of the plate, a rod passing through the eyes, a right angle extension formed on one end of the rod, a rod formed on the right angle extension and extending parallel with the first mentioned rod, a plate having eyes on the upper edge to receive the second mentioned rod, washers carried on each rod, the washers on one rod engaging the upper edge of the first mentioned plate, and the washers on the other rod engaging the upper edge of the second mentioned plate, plates carried by the rods on each side of the washers, and means for adjusting the plates to frictionally engage the washers.

2. A razor blade guard comprising a plate, the lower edge of which is offset, depending 95 tongues formed on the offset portion, a U-shaped spring having one arm secured to the plate and the other arm adapted to engage the blade, and guard means attached to said plate.

3. A razor blade guard comprising a plate, the lower edge of which is offset, depending 100 tongues formed on the offset portion, a U-shaped spring having one arm secured to the plate and the other arm adapted to engage the blade, and a plate hingedly secured to the first mentioned plate and adapted to be swung to either side of the blade.

4. A razor blade guard comprising a plate, the lower edge of which is offset, depending 110 tongues formed on the offset portion, a spring comprising a pair of parallel arms being connected by a curved cross piece, one of said arms adapted to be secured to the plate and the other arms adapted to engage 115 the blade so as to extend longitudinally therewith, the cross piece adapted to engage the thickened portion of the blade, and guard means connected to the plate.

5. A razor blade guard comprising a plate, 120 depending tongues formed thereon, a U-shaped spring having one arm secured to the plate and the other arm adapted to engage the blade, and guard means connected to the plate.

6. A razor blade guard comprising a plate, the lower edge of which is offset, depending tongues formed on the offset portion, a spring secured to the plate and adapted to engage the blade, and a secondary plate 130

hingedly connected to the first mentioned plate, eyes formed on the upper edge of the first mentioned plate, a rod passing through the eyes, a rod extending parallel with the first mentioned rod, means connecting the rods at one end, a secondary plate hingedly connected to the second mentioned rod, means for adjusting these two plates, and

means for securing the plates in their adjusted positions. 10

In testimony whereof I affix my signature in presence of two witnesses.

WILLIAM A. SNYDER.
